CLAIM

The ornamental design for a baby movement indicator, as shown and described.

DESCRIPTION

FIG. 1 is a perspective view of the baby movement indicator showing our new design wherein a claimed infant portion and plurality of unclaimed items are shown floating in a contained media;

FIG. 2 is a top plan view thereof;

FIG. 3 is a bottom plan view thereof;

FIG. 4 is a rear elevation view thereof;

FIG. 5 is a right elevation view thereof;

FIG. 6 is a front elevation view thereof; and,

FIG. 7 is a left elevation view thereof.

The broken lines in the figures show environment for illustrative purposes only and forms no part of the claimed design.
